UNITED STATES PATENT OFFICE

HAROLD E. HALLENBECK, OF HUDSON, NEW YORK, ASSIGNOR TO GIFFORD-WOOD COMPANY, OF HUDSON, NEW YORK, A CORPORATION OF NEW YORK

HOPPER GATE

Application filed April 16, 1929. Serial No. 355,517.

This invention relates to improvements in hopper gates which are particularly adapted for use in connection with traversing hoist buckets in material handling plants, and among other objects, aims to provide a gate held in closed position by a latch which is automatically released to permit the gate to open, when the bucket is lowered to filling position, the gate being closed by the bucket when hoisted.

This invention is an improvement on a pending C. M. Root application, Serial No. 78,163, filed December 29, 1925, and assigned to the assignee of this application.

In the drawings:—

Fig. 1 is a vertical longitudinal sectional view of a bucket loading pit and hopper, and showing one embodiment of the invention in connection with a gate and hoist bucket;

Fig. 2 is a similar view but showing the gate and bucket in different positions;

Fig. 3 is a fragmentary side elevation partly in section of the lower portion of the gate, drawn on a larger scale; and

Fig. 4 is a sectional view taken on the line 4—4 of Fig. 3.

Referring particularly to the drawings, the bin or hopper 10 has an outlet 11 with a spout or chute 12 secured to the bin and extending downwardly and outwardly from the outlet 11 so that the contents of the hopper may be discharged by gravity.

The chute 12 extends into a pit 13 and a traversing hoist bucket 14 is adapted to be lowered into the pit in position to receive material from the hopper. Instead of a pit, an above-ground pocket may be employed when the contour of the ground permits. The bucket is guided into and out of the pit by means of rollers 15 arranged in two pairs, one on either side of the bucket, the pairs of rollers being engageable with spaced inclined tracks 16, so that the bucket is maintained in upright position as it is lowered and elevated within the pit. The bucket may be hoisted and lowered by means of a cable 17 connected to any suitable hoisting mechanism (not shown) and passing around a sheave 18 mounted on a bail 19 pivoted on the bucket. A suitable abutment 20 is ar-

ranged to close the bucket when it reaches filling position (Fig. 2), substantially as disclosed in Patent No. 1,741,123 dated December 24, 1929.

The hopper is adapted to be closed by a gate of the radial undercut type, an example being the gate of the aforesaid C. M. Root application, consisting of a pair of side frames 21 pivoted on opposite sides of the hopper, as at 22, and connected at their outer ends by a plate 23, which is curved coaxially with the pivots 22. The outer edges of the side walls of the chute 12 are correspondingly curved to conform to the surface of the plate 23, and the plate is of sufficient length so that when it is raised (Fig. 1), the hopper outlet 11 is completely closed.

An extension chute 24 is rigidly secured to the upper ends of the frame 21 and its bottom wall is connected to the top of the plate 23 so that when the gate is lowered to the position shown in Fig. 2, the material from the hopper flows through the chute 12 and extension chute 24 into the bucket until the latter is filled. A pair of flapper arms 25 are pivoted to the bottom of the chute near its rear end and are connected by a cross rod 26, as best shown in the aforesaid C. M. Root application. When the gate is lowered (Fig. 2), the arms rest on the upper edge of the bucket and the gate is supported on the cross rod, so that when the bucket is raised, the arms are carried upwardly by the edge of the bucket, and the rod engaging the bottom of the chute raises the latter and closes the gate.

It will be clear that the engagement of the pairs of rollers 15 with the double guides or tracks 16 prevents tipping of the bucket under the reaction of lifting the gate, and hence obviates spillage of the material in the pit.

According to the present invention, the gate is arranged to be normally closed and locked in closed position and means are provided so that the gate will be unlocked by the bucket and then will open by gravity as the bucket approaches filling position. To control the gravity opening of the gate, a rope 27 is attached at one end to the upper end of the extension chute 24 and passes upwardly

over a sheave 28 and downwardly around a guide sheave 29 mounted on the wall of the pit below the hopper, the other end of the rope supporting a counterweight 30. The 5 weight of the gate is greater than the effective weight of counterweight 30 so that when unlocked, the gate falls by gravity to open position, Fig. 2.

To hold the gate in closed position (Fig. 10 31), a pair of latches 31 are provided on chute 12. These latches are preferably slidably mounted in the parallel flanges of a channel member 32 (shown best in Fig. 3), having its connecting web secured transversely of 15 chute 12 to the bottom wall 33 thereof and at the outer end. Each latch is normally urged outwardly by means of an expansile coiled spring 34 surrounding the latch and extending between the rear flange of the 20 channel and a collar 35 secured to the latch. The lower edge of the curved plate 23 is preferably reinforced by a metal plate 36 extending to the lower marginal edge of the plate 23 and nearly to the side edges. See 25 Fig. 4. When the gate is closed, the latches extend outwardly beneath the lower edges of the plates 23 and 36, both of which extend slightly below the bottom wall 33 of the chute. When the latches are moved rear- 30 wardly against the tension of the springs to clear the lower edges of the plates 23 and 36, the gate will fall by gravity to open position.

In order to automatically operate the latches so that the gate will be open when the 35 bucket is in filling position, a latch trip is provided for each latch and is arranged to be actuated by the bucket. In some instances, only one latch will be used.

Herein, the latch trips are in the form of 40 bell-crank levers 37 pivoted between angle brackets 38 on the lower end of the plate 23 and in vertical alignment with the bolts 31. The latch trips hang downwardly by gravity, and when the gate is closed, (Figs. 1 and 3) 45 the heel portions 39 rest against the outer ends of the latches 31 while the toe portions 40 extend downwardly and outwardly into the path of travel of the upper adjacent edge of the bucket. As the bucket, on being lowered 50 into the pit, nears its filling position, the upper side of the bucket nearest the gate strikes the toes 40 of the trips 37, swinging them downwardly and causing the heels 39 to move inwardly to force the latches 31 55 from beneath the gate to permit it to open by gravity. In view of the fact that the bucket strikes the latch trips before it reaches its lowermost position (Fig. 1), the chute is practically in filling position in the upper 60 open end of the bucket when the bucket comes to rest on the abutment 20. As the gate, on being released, moves downwardly, the inner face of the front plate 23 slides over the outer ends of the bolts and holds them inwardly 65 against spring tension. When the bucket is

raised, the gate is raised (by virtue of the arms 25 engaging the upper edge of the bucket) and when the lower edge of the gate clears the bolts, they are automatically projected beneath the plate 23 to hold the gate 70 closed. As clearly shown in Fig. 3, the rear portion of each lever above the heel is under-cut as at 41, so as to provide clearance for the rear portion of the heel when it swings toward plate 23 to release the latch. 75

In order to obtain a quick positive start of the gate downwardly when released, the sheave 28 is located so as to be approximately above the outer end of the extension chute 24 (Fig. 1) and the rope 27 is connected 80 to the top of the extension chute approximately midway between its ends. By this arrangement, the rope extends from the sheave downwardly to the extension chute, toward the gate pivot 22; and when the gate 85 is released for a short distance it descends without great resistance from the weight 30. However, as the gate falls, the moment arm between the cable connection to the gate and the pivot lengthens, reaching its maximum 90 just before the chute comes to rest on the bucket. Thus the gate is slowed up near the end of its fall by the increasingly effective restraining pull on the weighted rope; and as the gate is only slightly heavier than the 95 weight, the force of the impact between the chute and the bucket is reduced to a minimum. This saves wear and tear on the various parts, thus reducing the cost of maintenance and minimizing repairs. 100

It will be clear that when the bucket is lowered, the gate is automatically released to open by gravity, and when the bucket is hoisted, the gate is automatically closed and latched. Thus the gate is automatically controlled by the bucket and yet no part of the gate or the chute attached to it comes in contact with the bucket. 105

Obviously the present invention is not restricted to the particular embodiment thereof 110 herein shown and described.

What I claim is:—

1. In combination, a gate pivoted on a support and adapted to close a hopper, when raised, and to open by gravity; a hoist bucket 115 adapted to be lowered into filling position beneath the gate; latches slidably mounted on the bottom of the hopper; springs for projecting the latches into position to hold the gate closed; trip levers pivotally mounted on the gate and arranged to release the latches; said levers being engageable by the bucket when the latter is lowered to release the latches to permit the gate to open. 120

2. In combination, a hoist bucket; a combined gate and chute pivoted on a support and adapted to discharge material into the bucket when lowered and adapted to close the hopper when raised; a weight connected to the gate and chute assembly to partially 125 130

balance the same; said gate and chute being movable to filling position by gravity; slideable spring-pressed latches projecting beneath the gate to hold the latter in raised 5 position; trip levers pivoted on the gate and each having two arms; one of the arms of each trip lever being engaged with one of the latches when the gate is closed and the other arm extending into the path of travel of the 10 bucket and engageable by said bucket when lowered to release the bolt to permit the gate to open.

3. In combination, a chute; a pivoted gate adapted to gravitate to open position when 15 released; said chute having curved lower side edges, and the gate having a curved plate co-operating with said curved edges to stop flow of material down the chute; means for releasably holding the gate in closed position 20; said means comprising a channel member secured to the bottom of the chute; latches slidably mounted in the flanges of the channel and extending beneath the lower edge of the curved plate; an expansile coiled spring to 25 hold the latch in extended position; and trip means on the gate for releasing the latches to permit the gate to open.

4. In combination, a chute having the lower end terminating in arcuate edges; a closure 30 gate for the chute adapted to gravitate to open position when released; said gate comprising a pair of frames arranged at opposite sides of the chute and pivoted thereto; a curved plate secured between the outer ends 35 of the frames and co-operating with the arcuate edges of the chute to close the latter when the gate is raised; means for releasably holding the gate in closed position; said means comprising a latch; a hoist bucket adapted to 40 be lowered into filling position beneath the gate; and a pivoted bell-crank lever associated with the latch and having a short arm engageable with the latch and having a longer arm arranged to be engaged by the bucket when 45 the latter is lowered, whereby the gate is automatically opened.

In testimony that I claim the foregoing as my own, I have hereto affixed my signature.

HAROLD E. HALLENBECK.
